SOAP-MAKING PROCESS AND PRODUCT

William A. Kelly, Teaneck, N.J., assignor to Lever Brothers Company, New York, N.Y., a corporation of Maine

No Drawing. Filed Jan. 26, 1960, Ser. No. 4,626
6 Claims. (Cl. 252—122)

This invention is concerned with a novel process for the manufacture of superfatted transparent soap and with the products obtained by the process which also possess all the desirable properties of the highest quality milled soap.

Although it has been appreciated that soaps ordinarily identified as milled soap have some small degree of translucency, they have no transparency and are not considered by those skilled in the soap art as transparent soaps. Soaps are known in the art as transparent soaps, however, and some have enjoyed for many years a limited commercial appeal. Such soaps, however, are expensive due to the method of making them, and those so-called transparent soaps which attempted to use cheaper methods of production are no longer found to be acceptable by present day commercial standards.

One method used in the production of the more acceptable type of transparent soap is to prepare a soap base of reduced moisture content and then dissolve the soap in alcohol, removing the saline impurities by decantation. Alcohol is recovered from the soap by distillation. The soap mass is then cooled to solidify and mold. This method is expensive, time consuming, and involves the use of a high cost solvent.

A cheaper method for manufacturing a transparent soap used the well known cold process technique. Tallow which is low in free acid, coconut oil and rosin are saponified with caustic soda in the presence of alcohol or alcohol and glycerine or in the presence of a sugar solution, and the soap mass recovered and molded.

Another method involves the semi-boiled process and includes crutting the initial oils and fats at approximately 140° F., saponifying with caustic, then adding lye, and stirring until the soap has reached a desired consistency. This is followed by adding sugar dissolved in water, or alcohol and glycerine or combinations thereof. The mass is again crutched at about 160° F., and desired perfume and dyestuff added. The soap mass is molded by framing, then slabbed, cut and pressed. It is well known that neither the cold process nor the semi-boiled process produced soaps of high quality.

Prior art processes for the production of transparent soap are discussed by F. W. Wells in "Soap and Chemical Specialties," volume XXXI, No. 6 and No. 7, June and July 1955. As is mentioned in these articles, a transparent soap should be sufficiently transparent to permit bold-faced type of about 14 point size to be read easily through a thickness of a quarter inch. It is with reference to this standard that the term "transparent" is used in this application in describing products of the present process.

The incorporation of free fatty acid, such as palmitic, stearic acid, and others into a transparent soap bar to attempt to form a superfatted transparent soap bar would be desirable in that it eliminates free alkali, lowers the pH and generally makes the soap milder. It also improves the lathering characteristics of the bar. The addition of free fatty acid to the soap bar, however, has a major disadvantage in that it softens the bar usually to such an extent that the moisture content must be lowered to make the bar commercially acceptable. Moreover, the presence of free fatty acids makes it difficult to process the bar during plodding and stamping and destroys the transparency.

2

In accordance with the present invention these poor characteristics of superfatted soap bars are eliminated and superfatted transparent soap bars are obtained with all the desirable properties of the highest quality milled soap. This is achieved by the addition to a superfatted soap of a polyhydric alcohol, such as glycerine, sorbitol, sugar and pentaerythritol. The presence of a polyhydric alcohol in superfatted soap toughens it so that it can be milled and plodded in the normal manner. In most cases superfatted bars made with polyhydric alcohol are more "transparent" than bars made of the same base without superfat, with or without polyhydric alcohols. This is surprising since at room temperature stearic acid is a white opaque solid and most solids with these physical properties would opacify the bar.

The amount of free fatty acid that can be added is dependent on the amount of polyhydric alcohol used. When the free fatty acid content is increased, the polyhydric alcohol content must also be increased. For best results the quantities of each should be about equal, but the presence of more polyhydric alcohol than free fatty acid will not generally hurt the transparency. On the other hand, if much more free fatty acid than polyhydric alcohol is present in the soap bar, it tends to become soft and loses transparency. The free fatty acid content should not be more than 1% greater than the polyhydric alcohol content, both amounts being by weight of the finished bar. For example, if a bar contains 3% free fatty acid, it will not be transparent unless at least 2% polyhydric alcohol is present in the bar. In general the superfatted transparent bars will contain from about 1% to about 5% by weight of free fatty acid, and polyhydric alcohol in an amount up to about 10% by weight.

The salt and moisture limits to obtain transparency of the superfatted bars are not as critical as for non-superfatted bars. In general the moisture content of the finished bars will be in the range from about 17% to about 22.5% by weight and the salt content thereof will be from amount up to about 10% by weight.

The primary advantage of the method of this invention is that it makes possible the economical production of a superfatted transparent soap having excellent lathering properties, firmness and a smooth appearance and waxy feel. The superfatted transparent soap can be produced without waste or time loss and with minimum cost. There is no solvent used which must be recovered. No unusual equipment not available in ordinary soap making is required.

The superfatted transparent soap produced by the present invention has a pleasing firm yet velvety texture. During washing it does not form a mushy coating on its surface, and does not mar the appearance of the soap dish. It does not tend to form unsightly cracks, as is the case with many milled soaps. If the soap of the present invention is maintained for considerable lengths of time in contact with water, as happens occasionally when an incompletely dry soap dish is used, it may become cloudy as to that contacted portion, but the soap, upon removal from such contact, will return to its original firmness and transparency. Furthermore, and most surprisingly, bars of soap made by the process of this invention have the very desirable and unique advantage that they may be used even though worn to wafer thinness. Waste is therefore avoided.

Soaps may range from opaqueness through a translucency into true transparency, depending upon the method of manufacture. Various methods have been used to evaluate the translucency, and more specifically the transparency of soaps. A method for accurately measuring this property of a bar of soap is by the use of the following apparatus developed for this purpose. A bar of

soap is placed, in a completely darkened room, on top of a cone section surrounding a light source of variable voltage. The cone section has a diameter of $\frac{1}{2}$ inch at the top and $2\frac{1}{2}$ inches at the base, which surrounds the face of the light; the top of the cone section is $9\frac{1}{2}$ inches above the face of the lamp, and the lamp is a microscope lamp with a 120-volt, 15-watt bulb having a blue ground-glass filter. The voltage across the lamp bulb is adjusted until the light from the top of the cone section shines through a bar having a thickness of 2.75 cm. and forms a barely perceptible circular outline. The voltage across the bulb is used as a measure of translucency, which is independent of color and is termed "Translucency Voltage" or "TV." Thus, the lower the TV is, the more translucent the bar. It is possible to measure readily the TV at other bar thicknesses and interpolate to the standard of 2.75 cm. used herein. This method of determining translucency is believed to be superior to a reflectance test described in the art, because it is relatively unaffected by soap color and gloss and avoids the difficulty of cutting a soap bar to a required thickness of only $\frac{1}{16}$ of an inch.

For purposes of comparison, an ordinary milled toilet soap of good quality, even in the absence of pigments such as titanium dioxide which makes it opaque, has a TV of greater than 110, i.e., it is too opaque to be measured on the apparatus described. This is despite the fact that it has the sheen and glossiness which are commonly referred to as the translucency of milled soap, to distinguish it from the dull nature of frame soaps. The products of the present invention, on the other hand, have a TV of 35 or less, generally 30 or less, when freshly made. A bar of soap with a TV of 30 or less meets the standard required to be called transparent. In general, with the soaps of this invention there is an improvement in transparency upon aging of about six days or more, and in particular it is possible to practice our invention and produce a soap which, when fresh, may have a TV of more than 30, even as high as about 35, which soap, when aged, will acquire the transparent properties of a soap of a TV of about 30 or less. The difference between a bar of soap having a TV of 25 and one having a TV of 35 is quite obvious to the unaided eye.

The most convenient starting material for the present process is soap initially containing from about 28% to about 34%, usually approximately 30% to 32%, moisture, e.g., a neat kettle soap. The precise composition of the initial stock used to prepare the soap is not critical as long as the composition does not differ materially from those ordinarily employed in the manufacture of milled toilet soaps. Thus, for example, the relative proportions of fatty acids from tallow and from coconut oil, and the relative effects of such ingredients on the physical characteristics of milled toilet soap produced therefrom, are well known to soap makers, and this knowledge is applicable in the formulation of the soap stock used in the present invention. Tests conducted in developing the invention have indicated generally, for example, that the percentage of tallow soap in the soap portion of the final product preferably should be in the range of about 70% to 90%, the remainder being coconut oil soap or equivalent materials. A soap within this range of ratios has good use properties. The ratio of about 75% tallow soap to about 25% coconut oil soap is particularly good. Other oils which may be used in place of coconut oil are babassu, cohune, murumuru, ouricury, palm kernel and tucuna.

When neat kettle soap, which is in the liquid state, is used as the starting material, it is first subjected to ordinary crutching, during which the free fatty acids are added in order to eliminate the free alkali, lower the pH and form a superfatted soap. This crutching operation is not a critical feature of the invention and may be conducted by any conventional crutching method. The mixture during crutching is, as is conventional, in the liquid phase, at

4

a temperature above 180° F., and preferably above 205° F. The crutched kettle soap, which has a moisture content of from about 28% to 34%, usually approximately 30% to 32%, is next subjected to a drying step. The drying is carried out to an extent which permits the desired moisture range to be obtained in the finished bar. The drying step can be carried out by any of the conventional drying methods, for example, ordinary cabinet drying. It is, however, preferred to use the method commonly known as flash drying or, most preferably, the method of tubular drying as is described in U.S. Patent No. 2,710,057 of Bassett and Packard. When either flash drying or tubular drying has been used, the soap at the end of the operation will be in the molten state. It is then chilled and solidified, preferably into flakes or chips, before the mixing. There are some advantages, although not critical, in conducting the chilling operation rapidly. When ordinary cabinet drying is used, the soap will be in solid flaky or chip form after the drying.

While the free fatty acid is generally added in the crutcher, the polyhydric alcohol and salt may be added either in the crutcher or in the chip mixer discussed below.

The next operation is conveniently that of mixing the soap flakes. The polyhydric alcohol and salt may be added to the soap in the chip mixer. It is also a convenient time to adjust the water content and the salt content. The condition of the soap mass at the time of the mixing operation preferably should be one in which it will permit a working and shearing of the mass to be performed. For example, the soap mass should not be so hot that it is too soft or fluid to resist the operation of the mixer. For this reason, the temperature of the soap at the beginning of the mixing step should be below about 90° F., and preferably should be in the range of from 80° to 85° F. During the mixing of stocks of usual types and with usual mechanical equipment and time, the temperature should not rise above about 110° F., and preferably not above 104° F.

At some point, preferably before the end of the mixing step, the moisture content and the salt content must be adjusted so that in the finished product, they will be within the limits discussed above. During the mixing step, small amounts of various optional ingredients are added when desired. These include such substances as perfume, coloring materials, lanolin, resin, and preservatives. The presence or absence of any, some, or all of these optional ingredients is not controlling to the production of a superfatted transparent soap bar having the desired characteristics of a high grade milled soap.

Neat kettle soap is a convenient example of the soap stock used. It is, however, not necessary that this be the starting material. What is required is simply a soap mass, however prepared, which is capable of having its moisture and salt contents adjusted to the levels disclosed herein and to which can be added the free fatty acids and polyhydric alcohols. The drying of neat kettle soap is only one of the possible ways of obtaining such a soap and water mixture. An alternative method of obtaining the soap mass is, for example, the reaction between free fatty acids and alkali, to which reaction mixture water is added or removed as required in order to obtain a moisture content within the required range.

Particularly in the case of neat kettle soap which has been dried by the tubular or flash method and subsequently chilled rapidly, a satisfactory degree of transparency is obtainable as early as during the mixing step. To accomplish this, the amount of soap in the mixer and the type of mixer blades employed must be such that the soap offers a high degree of resistance to the motion of the blades; because of this resistance, the mechanical energy of the mixer blades is converted into heat energy, and the desired temperature of the mixture thereby obtained without addition of heat from an external source.

To obtain high degrees of transparency during the

mixing, the mixing is conducted for periods of time of about a half hour, the temperature thereby being raised to between 100° to 110° F., preferably to between 100° F. and 104° F. Generally in commercial production it is not convenient to spend this amount of time in mixing, since the desired transparency is more conveniently obtained during the subsequent milling, which need be no more than a nominal amount. The time of mixing generally employed is therefore about 15 minutes, although as little as about 4 minutes is enough to obtain satisfactory blending in of the polyhydric alcohol, salt, and other added materials, such as perfume or dye. The amount of working required will vary somewhat depending upon the particular soap stock and the particular working device used. The mixing times mentioned above are those for a Barbour-Stockwell mixer with thick counter-rotating blades. It is, however, a matter of routine testing to find the preferred conditions when other types of working are used.

It should be understood, however, that it is not critical to the process of preparing a superfatted soap bar of satisfactory transparency that any particular type of mixer be used, or that there be any mixing step at all. Rather, the type of mixer is of consequence only in those cases where it is desired to obtain a high degree of transparency during the mixing stage rather than at a different stage. It should also be understood that in order to obtain a high degree of transparency during the mixing, it is necessary that the mechanical energy of the moving mixer blades be taken up by the soap in the form of heat energy. Thus, a high degree of transparency will not be obtained during the mixing when a mixer with blades which pass through the soap without encountering much resistance is used along with heat supplied externally.

It is detrimental to the obtainment of transparency, not only during the mixing but at any subsequent stage, to allow the temperature of the soap mass to be above about 110° F. Preferably, the temperature is kept below 104° F.

The working effect of mixing is preferably amplified by subjecting the soap mass to milling. A single pass over two five-roll mills is normally sufficient. In order to obtain a satisfactory degree of transparency, it is critical that as the soap mass emerges from the mill it be at a temperature of from 100° F. to about 110° F., preferably from 100° F. to 104° F. Soap not already transparent becomes so during milling, provided it has the correct free fatty acid, polyhydric alcohol, salt and moisture content, and provided suitable critical temperatures have been maintained. It is to be understood that a refiner of the type described in Patent No. 2,005,333 may be substituted for the usual mill rolls and mixer, assuming always that the same suitable conditions are maintained relative to the soap stock used. It is thus seen that what is required to make transparent soap by the process of the present invention is that a soap mass having the specified proportions of free fatty acid, polyhydric alcohol, salt and water be subjected to working, its temperature raised to within the range of 100°-110° F., preferably 100° F.-104° F., and subsequently formed into bars. The working may take place during a mixing and/or a milling operation.

One of the functions of the milling operation is that the soap emerges from the mill in the form of very thin, flaky layers suitable for compacting by plodding into a bar form. The remaining steps in the conversion into bar form are not critical features, and are successfully accomplished by any conventional means. There is, however, an advantage to the use of vacuum plodding, since it most conveniently prevents air from becoming entrapped in the soap bar and thereby impeding translucency. It is advantageous that the soap leave the plodder at a temperature of from 98° to 110° F., preferably from 100° F. to 104° F. After the plodding, the soap is cut into individual cakes by usual means.

As has been mentioned above, it is critical to the proc-

cess of this invention that, at least before the end of the working, the free fatty acid, polyhydric alcohol, water and salt contents be adjusted so that the finished soap has a content thereof within the range specified above. During the milling and plodding operation, a certain portion of the water, usually an amount sufficient to reduce its percentage in the mixture by about 2 to 3, may be lost by evaporation, and this loss must be borne in mind when the water content is adjusted.

When in the specification and the claims the term "salt" is employed, particular reference is made to sodium chloride, but it is also intended to include other water-soluble, soap-compatible electrolytes such as potassium chloride and sodium sulfate.

Throughout the entire specification and in the claims, all percentages are percentages by weight.

The following examples are given solely for the purpose of illustration and not to be deemed limitations of this invention, many variations of which are possible without departing from the spirit or scope thereof.

EXAMPLE 1

Kettle soap having a base stock of 85% sodium tallow soap, 15% sodium coconut oil soap and containing about 32% water was charged to a crutcher. Sufficient stearic acid was added so that when the soap was dried and finished at 20% moisture it would contain 2% free stearic acid. The batch was heated to 210° F. and then dried to about 20% moisture by tubular drying. The soap was cooled and formed into chips on a chill roll and then placed in a chip mixer. Glycerine (2% of finished bar), dispersible pigments, perfume, salt to total 0.6% in the finished bar, lanolin (1% of finished bar) and about 2% water (dependent on the soap chip moisture) were added to the soap and the batch mixed for about 1/2 hour. The soap was milled by passing it over two 5 roll mills and then vacuum plodded. The temperature off the mills and out of the plodder was about 100° F. The bar was highly transparent and possessed good milled soap properties.

EXAMPLE 2

For this test the final product had the same composition as in Example #1 except no lanolin was added. Soap, glycerine, and stearic acid were mixed together and dried in the molten condition using a steam heated, open Paterson mixer. The dried chips were processed by passing the soap over a three roll mill, five times, and then vacuum plodding. The bar was highly transparent, tough and waxy.

EXAMPLE 3

A bar was made as in Example #2 but no glycerine was added. This comparative bar was very soft and had poor translucency, thereby illustrating the importance of having a polyhydric alcohol present in the bars of the invention.

EXAMPLE 4

Kettle soap (85% sodium tallow soap), 15% sodium coconut oil soap, 32% H₂O, glycerine (2% on finished bar), stearic acid (2% on finished bar) were mixed in a crutcher at 210° F. and tubular dried to 22% H₂O. There was no salt in this mixture. A series of bars were made by the finishing process as in Example #2 at various salt contents. The results were as follows: All bars contained 1% lanolin.

Bar No.	Percent NaCl	T.V.	H ₂ O
1	.6	18	19.6
2	.4	20	18.8
3	.0	145	18.4
4	.8	18	18.4
5	1.0	20.5	19.0

Bar No. 3 illustrates the importance of the salt content in the superfatted transparent bars of the invention.

EXAMPLE 5

A batch of soap was processed as in Example #2, then milled and plodded into bars. Samples were saved and then the soap was remilled and again plodded to lower the moisture content; this was repeated to obtain a moisture range. The NaCl content was 0.47%. The free fatty acid was 2.91%, and the glycerine 2.25%. The results were as follows.

TV:	H ₂ O, percent
17	22.3
14	21.4
14	18.0
20	17.4

EXAMPLE 6

An attempt to make a bar with 4% stearic acid and only 2% glycerine was a failure. The soap was soft, mushy and opaque. This comparative test demonstrates that the free fatty acid content must not be more than 1% greater than the polyhydric compound content, based on the final bar composition.

EXAMPLE 7

A bar containing 4% glycerine and 4% stearic acid was made by this process. (TV=18 transparent). The bar was tough, waxy and transparent. H₂O=20.0%.

The moisture content of the finished bar was 22.0%; its salt content was 0.45%; its TV was 20.

EXAMPLE 10

5 A bar was made according to the process of this invention from a soap having a base stock of 70% sodium tallow soap and 30% coconut oil soap. Sufficient stearic acid and glycerine were added so that the finished bar contained 2% stearic acid and 3% glycerine. The moisture content of the finished bar was 18.2%; its salt content was 0.37%; its TV was 23.

EXAMPLE 11

15 Using an arm immersion technique, bars containing 2% free stearic acid and 2% glycerine were judged significantly milder and caused significantly less burning sensation than Ivory soap, a product having a reputation of mildness. In this test the subjects immersed their arms in 1% solutions of the products being tested, three times daily for 15 minute intervals. The temperature of the solution was maintained at 105° F. The test was continued until irritation developed on the subjects' arms. Mildness in the arm immersion test was expressed as the number of the immersions for moderate irritation to develop. In the test the subjective reactions to the solutions regarding burning or smarting were also recorded. The data recorded in the following table indicate that soap produced according to the method of the present invention is significantly milder than Ivory from the standpoint of subjective reactions and development of irritation.

Mildness Comparison

TRANSPARENT SUPERFATTED SOAP VS. IVORY BAR AT 1% CONCENTRATION

Transparent Super-fatted Soap ¹	Ivory Bar	Arm Immersion Rating			Burning Sensation		
		No. of Subjects	Equal Mildness	Trans-p er-fatted Soap Milder	Ivory Milder	Ivory	Trans-p er-fatted Soap
1	A	11	3	7	1	10	1
2	B	13	10	8	0	13	0
3	C	10	4	5	1	9	1
4	D	9	7	2	0	9	0
Total		43	24	17	2	41	2
							0

¹ All the bars contained 15% coconut oil soap, 85% tallow soap, 2% Emersol 132 and 2% glycerine. In addition bars 2 and 4 contained 1% lanolin.

EXAMPLE 8

The following bars were made by the process described in this application. The results are listed below to further show the scope of the invention.

Bar No.	Base Stock	Free Fatty Acid	Polyhydric Alcohol	NaCl	H ₂ O	TV
1	85% sodium tallow soap; 15% sodium coconut soap	2% stearic	2% sorbitol	.65	21.0	14
2	do	do	2% sugar	.65	19.7	22
3	do	5% stearic	5% glycerine	.65	18.5	15
4	do	3% stearic	do	.48	19.6	14
5	do	4% stearic	do	.48	18.0	26
6	do	5% stearic	1% glycerine	.48	20.6	(1)
7	do	4% stearic	4% sorbitol	.48	19.6	19
8	do	2% stearic	10% sugar	.48	18.0	19

¹ Opaque.

Bar No. 6 illustrates the undesirable results obtained when the free fatty acid content exceeds the polyhydric compound content by more than 1% based on the final bar composition.

EXAMPLE 9

A bar was made according to the process of this invention from a soap having a base stock of 80% sodium tallow soap and 20% coconut oil soap. Sufficient stearic acid and pentaerythritol were added so that the finished bar contained 2% stearic acid and 1% pentaerythritol.

50 What is claimed is:

1. A process for making a superfatted transparent soap having a Translucency Voltage of no greater than about 35, said process comprising working below about

110° F., a toilet soap mass containing from about 1.0% to about 5.0% free soap-forming fatty acid and a polyhydric alcohol which overcomes the adverse softening effect of the fatty acid but does not deleteriously affect the transparency and processing characteristics of the bar in an amount up to about 10.0%, the quantity of said free fatty acid being at most 1% greater than the polyhydric alcohol content based on the final bar composition, wherein the mechanical energy is converted into heat energy by working to an extent great enough

to cause the mixture to rise in temperature to within a range of from about 100° F. to about 110° F., the moisture and water-soluble soap-compatible, alkali metal neutral salt content having been adjusted prior to the end of the working step to lie within the range from about 17.0% to about 22.5% moisture and an amount of said salt from about 0.2% to about 1%, and plodding the soap mass into bar form.

2. A process for making a superfatted transparent soap through which mass one-fourth inch thick, a 14 point boldface type is readable, said process comprising working at a temperature above 90° F. and below 110° F., a toilet soap mass containing from about 1.0% to about 5.0% free soap-forming fatty acid and polyhydric alcohol which overcomes the adverse softening effect of the fatty acid but does not deleteriously affect the transparency and processing characteristics of the bar in an amount up to about 10%, the quantity of said free fatty acid being at most 1% greater than the polyhydric alcohol content based on the final bar composition, whereby heat is generated throughout said mass by such working, reducing said mass at a temperature between 100° F., and 110° F. to a form suitable for plodding, plodding said soap mass into a bar form, the moisture and water-soluble, soap-compatible, alkali metal neutral salt content having been adjusted prior to plodding to the range of from about 17.0% to about 22.5% moisture and an amount of said salt from about 0.2% to about 1%.

3. A process for making a superfatted transparent soap having a Translucency Voltage of less than 35, said value being based upon the voltage required to transmit sufficient light from a 15-watt, 120-volt microscope lamp through a blue ground-glass filter at a distance of 9½ inches, to penetrate a 2.75 cm. thickness of said soap and for a circular outline therein, said process comprising working a toilet soap mass containing from about 1.0% to about 5.0% free soap-forming fatty acid and polyhydric alcohol which overcomes the adverse softening effect of the fatty acid but does not deleteriously affect the transparency and processing characteristics of the bar in an amount up to about 10%, the quantity of said free fatty acid being at most 1% greater than the polyhydric compound content based on the final bar composition, said soap mass having a 45

moisture content of from 17.0% to about 22.5% and an amount of water-soluble, soap-compatible, alkali metal neutral salt from about 0.2% to about 1%, whereby the temperature rises to not more than 110° F., reducing the mass to a ploddbable form, and plodding into bars while maintaining the temperature substantially uniform, whereby a waxy textured, transparent, isotropic, microcrystalline soap is obtained.

4. A superfatted transparent soap bar made from a toilet soap mixture, containing from about 1% to about 5% free soap-forming fatty acid and in which the final soap bar contains an amount of polyhydric alcohol which overcomes the adverse softening effect of the fatty acid but does not deleteriously affect the transparency and processing characteristics of the bar up to about 10%, from about 17.0% to about 22.5% water and from about 0.2% to about 1% water-soluble, soap-compatible, alkali metal neutral salt, the quantity of free fatty acid being at most 1% greater than the polyhydric alcohol content, which is worked within a temperature range of about 100° F. to about 110° F.

5. A superfatted transparent soap bar according to claim 4 which contains from about 1% to about 3% lanolin.

6. A superfatted transparent soap bar made from a toilet soap mixture, containing about 2% free soap-forming fatty acid and in which the final soap bar contains about 2% glycerine, about 0.6% water-soluble, soap-compatible, alkali metal neutral salt and about 20% moisture, the quantity of said free fatty acid being at most 1% greater than the polyhydric alcohol content, which has been formed by working at a temperature from about 100° F. to about 104° F.
